UNITED STATES PATENT OFFICE

96,877

DESIGN FOR A SHOE

Harry E. Williams, St. Louis, Mo.

Application July 15, 1935, Serial No. 57,634

Term of patent 3½ years

To all whom it may concern:

Be it known that I, Harry E. Williams, a citizen of the United States and resident of city of St. Louis, State of Missouri, have invented a new, original, and ornamental Design for a Shoe, of which the following is a specification, reference being had to the accompanying drawing, forming a part thereof.

Figure 1 is a perspective view of one side of a shoe; and

Figure 2 is a perspective view of the other side of a shoe, showing my new design.

The shading in the drawing is to illustrate contrasting colors.

I claim:

The ornamental design for a shoe, as shown and described.

HARRY E. WILLIAMS.
